Attorney

UNITED STATES PATENT OFFICE.

JOHN WM. KAYE, OF LULING, TEXAS.

TIE BUCKLE.

Application filed April 2, 1925. Serial No. 20,109.

To all whom it may concern:

Be it known that I, JOHN W. KAYE, a citizen of the United States, residing at Luling, in the county of Caldwell and State of Texas, have invented certain new and useful Improvements in Tie Buckles; and I do hereby declare the following to be a full, clear, and exact description of the invention, such as will enable others skilled in the art to which it appertains to make and use the same.

This invention relates to a buckle for use in connection with ties and particularly the steel ties as used on cotton bales and the like. It is aimed to provide a novel and simplified construction wherein the buckle is of greater strength than heretofore, more compact and lighter in weight.

Additional objects and advantages will become apparent from a consideration of the description following taken in connection with accompanying drawings illustrating an operative embodiment.

In said drawings:—

Figure 1 is a view in perspective showing the buckle connecting the ends of a tie, and

Figure 2 is a perspective view of the buckle alone.

Referring specifically to the drawings, the buckle is preferably made from a single blank of suitable metal as at 10 and has slots 11 and 12 of elongated form provided therein connected by a relatively narrow slot 13. Said slots 12 and 13 have lugs 14 between them and one on each side of the passage or slot 13. Said lugs are relatively wide and to this end, the slot 11 is relatively narrow, thus giving maximum width to the lugs 14 for the purpose of strength. One end of the slot 12 as at 15 is preferably tapered as shown. The buckle is preferably continuous marginally.

The buckle is used in connection with a tie as at 16, such as a metal tie as used on

cotton bales. The ends of such tie are 45 passed through the slots 12 and 13 as shown, the terminals thereof resting against the adjacent portion of the buckle and being compressed by the remainder thereof, the passage 13 enabling the tying of the tie with respect to the buckle to be carried out in the well known manner.

By the provision of the present buckle, it is considerably less in weight than existing constructions so as to reduce the cost of 55 transportation of bales or the like in connection with which it is used, when it is borne in mind that a number of these buckles are used with each bale. Also the buckle is considerably stronger than existing constructions which enables a less number of them to be used in connection with a bale. Furthermore, it is cheaper to manufacture than existing constructions and as well is easier to handle and much quicker 65 to effect buckling of the tie.

It is to be understood that the invention may be used in other relations than in connection with ties for cotton bales exclusively.

Various changes may be resorted to provided they fall within the spirit and scope 70 of the invention.

What is claimed is:—

A buckle of the class described comprising a single blank of metal continuous at 75 its edge, said blank being flat and having parallel elongated slots the same length and a relatively narrow slot connecting them, said slots providing parallel lugs, one of said longitudinal slots being rectangular and 80 relatively narrow to afford maximum width for the lugs, and the wider longitudinal slot having one end tapered from both side walls thereof, and said wider longitudinal slot being otherwise rectangular.

In testimony whereof I affix my signature.

JOHN WM. KAYE.
